FRIEDRICH LEDERER AND JOSEPH BERNARD LEDERER, OF MILWAUKEE, WISCONSIN,
ASSIGNORS TO NECEDAH MANUFACTURING COMPANY, A CORPORATION OF WIS-
CONSIN.

COMMUTATOR.

1,362,015.

Specification of Letters Patent. Patented Dec. 14, 1920.

Application filed May 11, 1917. Serial No. 168,022.

To all whom it may concern:

Be it known that we, FRIEDRICH LEDERER and JOSEPH BERNARD LEDERER, citizens of the United States, and residents of Milwaukee, in the county of Milwaukee and State of Wisconsin, have invented new and useful Improvements in Commutators, of which the following is a description, reference being had to the accompanying drawings, which are a part of this specification.

This invention relates to improvements in commutators for internal combustion engines.

In the ordinary commutator or timer for engines with a plurality of cylinders the fixed contacts are usually mounted circumferentially in spaced relation in a fiber bushing positioned within the commutator casing and the inner surfaces of the fiber and the contacts are turned flush to provide for the travel of the spring pressed roller of the revoluble brush contact extending into the casing and coacting with the fixed contacts. In use the arcing of the contacts causes pitting and the fiber becomes worn and the regular sequence of the electrical impulses to the engine will be interfered with unless the casing is removed and the fixed contacts and the insulating fiber ring are turned smooth and flush with respect to each other. This repair work requires time and careful work and the use of the engine is prevented until the timer is replaced. In removing the commutator casing it is of course necessary to disconnect all of the electric circuit wires from the casing.

It is one of the objects of the present invention to overcome the before mentioned objectionable features and provide a commutator in which the relatively fixed contacts are removably mounted within the casing and may be easily removed and replaced in a moment of time without the use of tools of any kind and without the necessity of doing any machine or other work on the casing or of disconnecting the electric circuit wires.

A further object of the invention is to provide a commutator in which the major portions of the parts may be formed of sheet metal.

A further object of the invention is to provide a commutator having means which permits the oiling of the interior of the cas-

ing without removing the casing from its support.

A further object of the invention is to provide a commutator which is of simple construction, is strong and durable and is well adapted for the purpose desired.

With the above and other objects in view the invention consists in the improved commutator and its parts and combinations as set forth in the claims and all equivalents thereof.

In the accompanying drawing in which the same reference characters indicate the same parts in all of the views:

Figure 1 is a transverse sectional view of the improved commutator taken on line 1—1 of Fig. 2, parts broken away, one of the contact members shown as bent for removal;

Fig. 2 is a vertical sectional view taken on line 2—2 of Fig. 1;

Fig. 3 is a sectional detail view taken on line 3—3 of Fig. 1;

Fig. 4 is a detail view of the oil device of the casing; and

Fig. 5 is a perspective view of the fixed contact holding member.

Referring to the drawing the numeral 8 indicates a support which may form part of the commutator or in the Ford engine may be part of the engine casing. As shown the support is provided with an annular recess 89 to receive the inner edge of the commutator casing 10 mounted thereon. The body portion 11 of the casing is of annular form and is closed on its outer side by the conical end portion 12 having an axial recess 13 for receiving the rounded end portion 14 of the case spring 15 which holds the casing yielding in the annular recess of the support.

A bolt 16 or other means connects the opposite end of the spring 15 to the support. 95

Fixed contact holders 17 mounted within the annular portion of the casing and spaced equidistantly apart circumferentially are insulated from each other and from the casing by a strip of fiber 18 and fiber washers 19 and 20. The body portions 21 of the contact holders are formed of sheet metal bent

into U-shape transversely of their length to form side portions 22 and spaced locking side ears 23. The side portions 22 have 100 pairs of contact holder fingers 24 bent at right angles therefrom and toward the space 23 and terminate between said locking ears.

The body portions 22 are provided with threaded stems 25 which extend radially through openings 26 in the casing and through the insulating strip of fiber 18 and 5 the fiber washers 19 and 20 before mentioned and on their outer end portions are provided with nuts 27 and 28. The nuts 27 bear against the washers 20 which are larger than the openings 26 and thus clamp the 10 contact holders in position, while the nuts 25 serve to connect circuit wires 29 to the stems and form electrical connections therewith. The strip of fiber is provided with inwardly projecting portions 18' which extend into registering openings 30' of the contact members to positively hold said contact members in circumferentially alined positions.

Contact members 30 removably mounted 20 on the fixed holders 17 are formed of strips of spring metal bent to form flat body or contact portions 31, yielding curved or folded over end portions 32 and inturned eyed ends 33 through which the contact 25 holder fingers 24 extend. The yielding end portions 32 are normally interposed between the side portions 22 and the side locking ears 23 and are securely and yieldingly held in position thereby when the eyed ends 30 33 surround the holder fingers 24. In order to remove or replace any one of the contacts it is only necessary to bend the curved end portions of the member toward each other and inwardly in the manner shown at 35 the lower right hand portion of Fig. 1 to clear the locking ears and the said member may then be easily slipped off or on the holder fingers.

The contact portions 31 are engaged by 40 the roller contact 34 which is carried by the roller arm 35 mounted on the shaft 36. The roller arm bears against a collar 37 formed on the shaft 36 and is held in position on the shaft by a transverse pin 38 and a nut 39 45 and a flanged collar 40 which overlaps the hub portion 41 of the roller arm. The roller arm is of sufficient length to cause the roller to firmly engage the yielding contact members and form an electrical contact 50 therewith.

In order to conveniently lubricate the working parts of the commutator an oil hole 42 is provided in the upper portion of the casing which is provided with a revoluble 55 semi-circular shaped cover 43 having an outwardly extending handle portion 44 for convenience in turning the same. The cover is revolvably held on the casing by a plate 45 having an embossed portion 46 for receiving 60 the cover and an opening 47 through which the handle 44 projects. The plate is provided with a radially extending portion 48 to form a handle for adjusting the casing to advance or retard the spark with relation to

the engine of which the commutator forms 65 a part.

The oil opening of the casing is of semi-circular form to correspond with the shape of the cover so that when the cover portion is turned a half revolution the oil opening 70 will be uncovered.

From the foregoing description it will be seen that the commutator is of very simple construction and is well adapted for the purpose described.

What we claim as our invention is:

1. A commutator, comprising a casing, a fixed contact holder mounted therein, a detachable contact member having end portions extending toward each other and carried by the contact holder and removable therefrom without removing any of the parts of the holder, and a revoluble contact arm extending into the casing and engaging the contact member.

2. A commutator, comprising a casing, a fixed contact holder mounted therein, a yielding contact member having end portions extending toward each other and slidably detachably connected to the contact 90 holder and removable therefrom without removing any of the parts of the holder, and a revoluble contact arm extending into the casing and engaging the contact member at each revolution.

3. A commutator, comprising a casing, a fixed contact holder mounted therein, a yielding contact member having eyed connections extending toward each other which are detachably connected to the fixed contact holder and detachable therefrom without removing any of the parts of the holder, and a contact-arm revolvably mounted within the casing and engaging the contact member.

4. A commutator, comprising a casing, a fixed contact holder mounted therein and provided with a projecting finger and locking ear, a yielding contact member formed of resilient material which is engaged by the locking ear and having a folded eyed portion into which extends the projecting finger, said contact member being removable from the holder without removing any of the parts of the holder, and a contact arm revolvably mounted within the casing and 115 engaging the contact member.

5. A commutator, comprising a casing, a fixed contact holder mounted therein and insulated therefrom, said contact holder on one side edge having a side wall provided 120 with laterally projecting fingers and on the other side edge having spaced locking ears, a yielding contact member having folded end portions and inner eyed ends into which extend the fingers, the folded end portions 125 extending between the side wall and the locking fingers and detachably held thereby, and a contact arm revolvably mounted

within the casing and engaging the contact member.

6. A commutator, comprising a casing having circumferentially spaced openings, 5 fixed contact holders having threaded stem portions which extend through the openings, means insulating the holders from the casing, nuts threaded on the stems, each of said contact holders on one side edge having 10 a side wall provided with laterally projecting fingers and on the other side edge having spaced locking ears out of alignment with the fingers, a yielding contact member for each contact holder consisting of a strip 15 of spring metal having folded and inwardly extending end portions provided with eyed ends into which extend the fingers, the folded end portions extending between the side wall and the locking ears, and a contact arm revolvably mounted within the casing and having a roller which successively 20 engages the contact members.

7. A commutator, fixed contact holder

and detachable contact, comprising a contact holder having a body portion provided with 25 a stem and on one side edge a side wall with laterally projecting fingers and on the other side edge having spaced side ears out of alignment with the fingers, and a detachable 30 spring metal contact having folded and inwardly extending end portions provided with eyed ends into which extend the fingers, the folded end portions extended between the side wall and the locking ears.

8. A detachable commutator contact, 35 consisting of a strip of spring metal having its opposite end portions bent inwardly toward each other and formed with adjacent eyes, the metal between the bent portions forming a yielding electrical contact surface of a 40 considerable length.

In testimony whereof, we affix our signatures.

FRIEDRICH LEDERER.
JOSEPH BERNARD LEDERER.
